UNITED STATES PATENT OFFICE.

LOUIS M. BROWN, OF BEVERLY, MASSACHUSETTS, ASSIGNOR TO UNITED SHOE MACHINERY COMPANY, OF PATERSON, NEW JERSEY, A CORPORATION OF NEW JERSEY.

METHOD AND APPARATUS FOR USE IN FORMING UPPERS OF BOOTS AND SHOES.

1,235,651.

Specification of Letters Patent.

Patented Aug. 7, 1917.

Application filed November 25, 1914. Serial No. 874,070.

To all whom it may concern:

Be it known that I, LOUIS M. BROWN, a citizen of the United States, residing at Beverly, in the county of Essex and State 5 of Massachusetts, have invented certain Improvements in Methods and Apparatus for Use in Forming Uppers of Boots and Shoes, of which the following description, in connection with the accompanying drawings, is 10 a specification, like reference characters on the drawings indicating like parts in the several figures.

This invention relates to methods and apparatus for use in the manufacture of boots 15 and shoes for the purpose of forming the upper materials, or portions thereof, in substantially the shape desired for the finished shoe before the upper has been brought into assembled relation to the materials 20 that constitute the bottom portion of the shoe. Machines of this class are applicable to the manufacture of shoes of different types but find their principal use at the present time in the manufacture of "stitch-down" shoes, in which the upper is provided 25 with an out-turned flange to receive the stitches or other fastenings by which the upper is secured to the sole. Such machines are shown, for example, in United States 30 Letters Patent No. 998,682, granted on July 25, 1911, upon the application of Karl Engel, and No. 1,181,296, granted on May 2, 1916, upon the application of Karl Engel and Louis M. Brown.

The machines described in the patents 35 above mentioned include, among other features, means for shaping the forepart of the upper, and according to the practice therein disclosed the marginal portion of the upper 40 at the toe end is confined between members that impart the necessary pressure to form the out-turned flange, and while the margin is thus subjected to pressure the unconfined portion of the blank is operated upon by a 45 toe former which imparts to the blank the shape desired for the forepart of the vamp in the finished shoe. This toe forming operation obviously requires a fullness of that portion of the material bounded by the 50 clamped margin, and by reason of the variation in contour at different parts of the toe of the shoe, there is a corresponding variation in the amount of material required for

shaping different portions. In order to avoid unduly straining or tearing the blank, 55 therefore, it is necessary to provide for some distribution of the material to meet the demands of the operation of the toe former. The machines disclosed in the patents above mentioned accordingly have provision for 60 suitable compensating movement of the flange portion of the upper materials, which is effected by providing clamp members with portions that are movable substantially in the plane of the clamp margin of the blank 65 to guide and impart to different portions of the blank at the margin movements in suitable directions and of sufficient extent to meet substantially the demands of the toe former and insure the formation of a smooth 70 toe without subjecting any portion of the material to excessive strains.

This invention, in a more particular aspect, relates to methods and apparatus for use in shaping the forepart or toe portion of 75 shoe uppers. One feature of the invention resides in mechanism of novel and improved construction for effecting suitable compensating movements of the marginal portion of the blank so as to insure the formation of a smooth toe without excessive strain upon the material.

Another feature resides in improved means for forming the flange on the blank, 80 by the operation of which the flange is ironed to cause it to retain the shape imparted to it by the clamping pressure, the ironing preferably taking place after the material at the margin of the blank has been gathered about the toe end.

These and other features of the invention, 85 and also the steps of the novel method herein disclosed, will now be described with reference to the accompanying drawings, which show an illustrative machine in which the 90 novel features of the invention are embodied and by the use of which the novel method may be practised, and will then be pointed out in the claims.

The invention is illustrated by reference 100 to mechanism suitable for use as part of the machine shown and described in Patent No. 1,181,296, only such portions of the machine being shown herein as are necessary for an understanding of the present invention. It 105 will be understood, however, that with ob-

vious changes the mechanism shown may be adapted for use in apparatus such as illustrated in the above mentioned Patent No. 998,682, or in other machines or apparatus 5 of the like general class.

In the drawings,

Figure 1 is a plan view, with portions broken away, of one form of apparatus illustrating the invention;

10 Fig. 2 is a section on line 2—2 of Fig. 1, showing the parts at a different stage of the operations;

Fig. 3 is a view similar to Fig. 1 showing an alternative form of apparatus; and

15 Fig. 4 is a section on line 4—4 of Fig. 3 illustrating the same stage in the operations as shown in Fig. 2.

In the apparatus shown the mechanism for confining and operating upon the marginal portion of the blank is mounted upon a supporting plate 2 which is adapted to be secured in its proper position as a part of the upper forming machine. This mechanism comprises coöperating clamp members 4 and 6, of which the member 4, shown fragmentarily in the drawings, is of well known form and has a smooth face to engage the upper or finished surface of the marginal portion of the blank around the 25 edge of the toe former 8. This member is upheld normally in a well known manner by springs 10 encircling the guiding rods 12 and is suitably operated, as will be readily understood, to cause it to approach the 30 plane of the lower clamp member and clamp the material. The mechanism for operating the toe former 8 is not shown herein in detail, but one form of mechanism for this purpose is fully disclosed in Patent 35 No. 1,181,296 above referred to. It is sufficient for an understanding of the present invention to state that after the margin of the blank has been clamped, the toe former receives a slight upward movement 40 and is then moved forwardly to form the toe simultaneously with the forward movement of a bar 14 which carries adjustable pushers 16 the purpose of which will be subsequently explained.

50 The lower clamp member, indicated in general by the numeral 6, comprises a plate which is mounted upon the support 2 for sliding movement forwardly against the force of a spring 18 which positions the 55 member normally at its limit of rearward movement determined by stops 20 on the support 2. Upon this plate, in the form of the invention shown in Figs. 1 and 2, are mounted a plurality of arms or levers 22 pivoted at 60 24 for swinging movement in a plane parallel to the plane of the plate 6 or to the plane of the clamped margin of the blank and having teeth at their ends for engagement with the margin of the material upon its 65 lower or unfinished surface. In the form

of the invention illustrated in Figs. 3 and 4 the levers 26 are similar in function to the levers 22 but are pivoted at 28 to swing about axes located inwardly from the edge of the clamped blank and their toothed 70 blank engaging portions are at some distance from their ends and swing in paths that curve about the blank margin. In both forms the levers are held normally by springs 30 at limits of movement determined by stops 32 which are mounted on longitudinally adjustable curved slides 34 held by screws 36 in adjusted position in a curved slideway 38 in the plate 6. Operative forward movement is imparted to 75 the levers from curved slides 40 mounted in a guideway 42 in the plate 6 and carrying pins 44 which are positioned upon each slide to engage the levers of the respective group in succession, beginning with the rearmost lever of the group, and thus to swing the blank engaging portions of the levers forwardly toward the toe end of the blank. The slides 40, in the form shown in Fig. 1, are engaged at their rear ends and 80 moved forwardly by bars 46 which are mounted in slideways at the rear end of the plate 6 and are engaged by the pushers 16 and moved forwardly at the beginning of the forward movement of the toe former 8 85 and the bar 14. In Fig. 3 the operating bars 48 for the slides 40, which are similarly advanced by the pushers 16, are mounted in extended guideways formed in the plate 6 below the plane of the guideway 42 and carry pins 50 which engage the 90 rear ends of the slides 40.

In order to carry forward the marginal portion of the material at the sides of the toe former in the rear of the levers, the 105 apparatus, in the form shown in Fig. 1, includes toothed slides 52 which comprise preferably lateral and upward extensions of the bars 46 and move therewith. The apparatus shown in Fig. 3 includes similar 110 slides 54 which are preferably integral with the bars 48, as shown. Both forms of the invention include also a plate 58 mounted upon the top of the rear portion of the plate 6 and cut away to permit the movements of the slides 52 or 54. This plate is curved at its forward edge to conform substantially to the curve of the toe former, and the forward portion of the plate formed as described has a function which will be 120 subsequently explained.

The operation of the described mechanism takes place after a toe blank, or the forepart of an upper, has been adjusted over the toe former 8 with its margin overlying the 125 toothed slides 52 or 54 and the toothed portions of the operating levers 22 or 26 which are in their idle positions as shown in Figs. 1 and 3. The margin of the blank is then clamped in position, as will be readily un- 130

derstood, through the movement of the clamp member 4, and the toe former 8 is then raised slightly and together with the bar 14 is moved forwardly to shape the toe. During the first portion of this forward movement the pushers 16 serve to advance the slides 46 or 48 in the clamp member 6 and thereby impart movement to the plates 52 or 54 and the levers 22 or 26, moving first that lever which is nearest to the rear of the clamp member on each side and bringing the other levers into operation successively in the manner previously explained. In this operation the slides 52 or 54 carry forward the material at the sides of the toe former, and the levers gather and move forward the material at the toe end, thereby effecting such gathering and compensating movement of the portions of the blank as to meet the demands of the toe former and permit the formation of a smoothly shaped toe without excessive strains upon the material. Before the completion of the forward movement of the toe former 8 the heads of the pushers 16 come into contact with the rear end of the plate 6. Movement of the slides and levers relatively to the plate 6 then ceases and the lower clamp member comprising the plate 6 and the mechanism carried thereby is advanced during the final stage of the operation of forming the toe. In this manner the compensating forward movement of that portion of the material which is engaged by the slides 52 or 54 is continued; but the clamp member 4 and the toe former press upon the blank sufficiently to prevent any material forward movement of the margin about the toe end, and in consequence the toothed portions of the levers about the end of the toe former slide from under the margin of the blank which is engaged immediately by the smooth plate 58 and ironed and pressed to assist in shaping the out-turned flange. The plate 58 may be heated if desired by means such as is commonly used in machines of this class for heating the toe former. After these operations the parts come to rest and are retained in the toe shaping relation illustrated in Figs. 2 and 4 a sufficient time to permit the blank to set in the form in which it has been molded. The toe former and the bar 14 are then retracted and the clamp members separated so as to release the work, permitting the lower clamp member to be returned by the spring 18 and the other parts of the apparatus to resume the positions indicated in Figs. 1 and 3, the return of the slides 40 being effected by the spring operated levers 22 or 26.

Although the invention has been described with reference to mechanism in which the operations upon the marginal portion of the blank take place simultaneously with the movement of the toe former, it should be un-

derstood that in the broader aspects of the invention it is immaterial at what particular stage the compensating movement is imparted to the margin of the blank or the ironing of the margin is effected, although the latter operation should be subsequent to the gathering of the material at the toe end. 70

The term "blank" or "toe blank" used in the claims is to be understood as referring generally to the materials which are to be operated upon, such, for example, as the forepart or vamp portion of an assembled shoe upper; such materials being suitably shaped for use in forming the toe of a shoe, or other like article of manufacture. 75

Having described the invention and set forth fully how the novel method may be practised, what I claim as new and desire to secure by Letters Patent of the United States is:—

1. In apparatus for shaping a toe blank, the combination with a toe former, of means for clamping the marginal portion of the blank to form a flange thereon, said means including a plurality of blank engaging 90 members pivoted for swinging movement in a plane substantially parallel to the plane of said clamped margin, and means for imparting swinging movement to said members while the margin of the blank is clamped by 95 said clamping means.

2. In apparatus for shaping a toe blank, the combination with a toe former, of means for clamping the marginal portion of the blank to form a flange thereon, said means including a plurality of blank engaging 100 members pivoted to swing about axes located inwardly from the outer edge of the blank, and means for swinging said members to gather the material at the margin of the 105 blank.

3. In apparatus for shaping a toe blank, the combination with a toe former, of means for clamping the marginal portion of the blank to form a flange thereon, said means including a series of blank engaging members pivoted for swinging movement in a plane substantially parallel to the plane of 110 said clamped margin, and means for imparting movement to different members of the series in succession to gather the material at the margin of the blank while the margin is clamped by said clamping means. 115

4. In apparatus for shaping a toe blank, a clamp member having a series of levers 120 pivoted thereon and provided severally with means for engaging the marginal portion of the blank, and operating means for said levers comprising a slide constructed to impart movement to different levers of the series in succession.

5. In apparatus for shaping a toe blank, the combination with a toe former, of a plurality of pivoted members constructed to engage the material at the margin of the blank, 130

- and a slide movable in a curved path about the margin of the blank and having means for engaging and operating said members.
6. In apparatus for shaping a toe blank, 5 a clamp member having a plurality of levers pivoted thereon and provided severally with means for engaging the marginal portion of the blank, a slide on said clamp member having projections for engaging and swinging the levers, and means for operating the slide.
7. In apparatus for shaping a toe blank, 10 a clamp member having a plurality of levers pivoted thereon and provided severally with means for engaging the marginal portion of the blank, stops for determining the idle positions of said levers, resilient means for holding the levers normally in contact with the stops, and means movable transversely of the levers for imparting operative movements thereto.
8. In apparatus for shaping a toe blank, 15 a clamp member having a plurality of levers pivoted thereon and provided severally with means for engaging the marginal portion of the blank, an adjustable slide on the clamp member provided with stops for determining the idle positions of said levers, and an operating slide having means for imparting operative movements to the levers.
9. In apparatus for shaping a toe blank, 20 a plurality of pivoted blank engaging members arranged to project outwardly in a series about the margin of the blank, movable slides curved about the blank and having means for imparting operative movement to different members of the series in succession, and means for imparting operative movement to said slides.
- 40 10. In apparatus for shaping a toe blank, the combination with a toe former, of means for clamping the marginal portion of the blank to form a flange thereon, said means including a plurality of members arranged to engage the marginal portion of the blank about the toe end thereof and pivoted for swinging movement in a plane substantially parallel to the plane of said clamped margin, movable slides having means for engaging the blank margin at the sides of the blank, and means for effecting operative movement simultaneously of said pivoted members and slides.
11. In apparatus for shaping a toe blank, 55 the combination with a toe former, of a plurality of blank engaging members arranged for relative swinging movements to gather the material about the toe end of the blank, means for operating said members, and means for moving forward the marginal portion of the material at the sides of the blank simultaneously with the operation of said members.
12. In apparatus for shaping a toe blank, 60 65 the combination with toe forming means, of means for forming a flange on the blank, and means for ironing the flange to cause it to retain the shape imparted thereto by said forming means.
13. In apparatus for shaping a toe blank, 70 the combination with toe forming means, of means for gathering the material at the margin of the blank, and means for subjecting said gathered material to rubbing pressure.
14. In apparatus for shaping a toe blank, 75 the combination with toe forming means, of means for clamping the material at the margin of the blank to form a flange thereon, means for gathering the material at said clamped margin, and means for ironing the margin of the blank to set the flange in permanent shape.
15. In apparatus for shaping a toe blank, 80 the combination with toe forming means, of clamp members relatively movable to clamp the margin of the blank, said members being relatively movable also to iron the blank.
16. In apparatus for shaping a toe blank, 85 clamp members relatively movable to clamp the margin of the blank, one of said members having blank engaging devices movable thereon to gather the material at the margin of the blank and an ironing member in the rear of said devices, said clamp member being movable forwardly to cause the ironing member to operate upon the blank.
17. In apparatus for shaping a toe blank, 90 clamp members relatively movable to clamp the margin of the blank, one of said members having blank engaging devices movable thereon to gather the material at the margin about the toe end of the blank and an ironing member in the rear of said devices, means for operating said devices to 95 gather the material, and means for subsequently moving said clamp member forwardly to cause the ironing member to operate upon the gathered material.
18. In apparatus for shaping a toe blank, 100 clamp members relatively movable to clamp the margin of the blank, one of said members having blank engaging devices movable to gather the material at the margin of the blank and also ironing means, and means for imparting relative movement to said clamp members to cause the gathered material to be ironed by said ironing means.
19. In apparatus for shaping a toe blank, 105 means for gathering and clamping the material at the margin of the blank comprising clamp members for confining the margin under pressure, and means for imparting relative movement to said clamp members to iron the gathered material.
20. The method of shaping a toe blank, 110 which comprises gathering in the material at the margin of the blank to provide a fullness in the portion of the material bounded by said margin, and ironing said gathered 115 material.

material under pressure to cause it to set in permanent form.

21. The method of shaping a toe blank which comprises clamping the marginal portion of the blank, gathering in the material along the margin of the blank while the clamping pressure is maintained, and then ironing the gathered material to cause it to set in permanent form.
- 10 22. The method of forming a flange on a toe blank which comprises clamping and

gathering in the material at the margin of the blank, and while the clamping pressure is maintained ironing said material to cause it to set in permanent form. 15

In testimony whereof I have signed my name to this specification in the presence of two subscribing witnesses.
